UNITED STATES PATENT OFFICE

ALEXANDER HORVATH, OF CHICAGO, ILLINOIS

APPARATUS FOR FORMING CRYSTALS

Application filed September 19, 1929. Serial No. 393,714.

This invention relates to the art of forming crystals, and particularly to apparatus for forming crystals for watch cases and the like. The particular embodiment of applicant's invention disclosed in the present application pertains especially to an apparatus for forming the crystals of watch cases.

It is a well known fact that watch cases, and particularly those worn on the wrist, are of various different sizes and shapes to attract the eye of the particular individual, and that whenever a crystal is broken, it is, in many instances, very difficult to replace the crystal without considerable delay and expense. This is particularly true in the case of crystals having odd shapes and sizes. Furthermore, watch cases being usually manufactured of relatively light material, the bezel thereof in which the crystal is mounted often becomes warped or the shape thereof otherwise distorted, thus making it very difficult if not impossible to secure therein a crystal which will provide suitable protection for the mechanism of the watch, even though the crystal furnished may be of the proper size and shape for that particular design of watch.

Furthermore, the large variety of designs and sizes in watch cases entails the necessity of carrying a large and varied stock of crystals in order to meet the possible demand for crystals of a particular design or size, and owing to the fact that a large portion of such a collection of crystals become obsolete and consequently dead stock, the price of an individual crystal is greatly increased. Furthermore, a stock crystal of proper dimensions to fit a particular bezel may be of insufficient height to avoid binding on the tips of the hands, thereby interfering with the efficient operation of the watch, and in such a case, any attempt to grind away a portion of the crystal usually results in the destruction or weakening of the crystal, or at best in producing a crystal of unsightly appearance.

One object of the present invention is to provide a device for making crystals for watch cases and the like, from a relatively thin sheet of pliable material, such as celluloid or other suitable material, and wherein the bezel of the case to which the particular

crystal is to be applied, is employed as a template in the formation of the crystal.

Another object of the invention is to provide an apparatus by means of which a crystal may be readily formed from a blank piece 55 of suitable material in such a manner that the crystal when finished will conform to the exact shape and size of the opening in the bezel in which the crystal is to be mounted.

Another object of the invention is to provide an apparatus for producing crystals of various heights thus obtaining the necessary clearance desired for the hands of the watch.

Another object of the invention is to provide an apparatus for forming crystals of any desired size, shape, pattern or design.

Another object of the invention is to provide a device for forming crystals of the unbreakable type at low cost, of correct size 70 and which will be very satisfactory for their intended purposes.

Another object of the invention is to provide suitable clamping means for securing the material from which the crystal is made 75 in desired position to permit of proper treatment of the material in the formation of the crystal.

Another object of the invention is to provide means for forming a crystal having a dome like portion of predetermined height, and means for varying the height of such portion as desired.

Another object of the invention is to provide suitable means for heating the material used in a manner to facilitate the treatment thereof in the formation of the crystal.

Another object of the invention is to provide for automatically controlling the operation of the heating means.

A further object of the invention is to provide means for varying the operation of the heat controlling means.

A still further object of the invention is to improve devices of the character disclosed in sundry details hereinafter described and particularly pointed out in the appended claims.

One embodiment of the present invention is shown for illustrative purposes in the accompanying drawings in which Fig. 1 is a plan view of a device embodying features of the present invention.

Fig. 2 is an elevational view of the device shown in Fig. 1.

Fig. 3 is a vertical sectional elevation taken substantially as indicated by the line 3—3 of Fig. 2.

Fig. 4 is a bottom plan view of a portion of the structure illustrated in Fig. 3, and taken substantially as indicated by the line 4—4 of Fig. 3.

Fig. 5 is a sectional top plan view of the doming gauge taken substantially as indicated by the line 5—5 of Fig. 3.

Fig. 6 is a top plan view of the base structure illustrating the application of a bezel adapter or spacing frame and centering ring thereon.

Fig. 7 is a side elevation of the bezel adapter or spacing frame and centering ring illustrated in Fig. 6.

Fig. 8 is a perspective view of the centering ring illustrated in Figs. 6 and 7.

Fig. 9 is a perspective view of the spacing frame illustrated in Figs. 6 and 7.

Fig. 10 is a perspective view of another form of spacing frame.

Fig. 11 is a perspective view of a portion of a strip of suitable material used in the formation of the crystal.

Fig. 12 is a perspective view of a portion of the sheet of material employed, after the formation of the crystal therefrom, and illustrates the formation or condition of the material after being treated by the apparatus shown in the illustrative embodiment of the invention.

Fig. 13 is a perspective view illustrating the completed crystal ready to be positioned in the bezel of a watch case or the like.

In the illustrative embodiment of the invention shown in the drawings, a base or housing 15 is provided, and shown in the present instance as mounted on a box like structure or case 16 provided with a drawer 17 which may serve as a receptacle for a supply of the material from which the crystals are to be made and for any tools such as a screw driver, file or other implements employed in the operation of the device.

Suitably mounted in the housing or base 15 preferably adjacent the upper portion thereof is a heating unit, designated as a whole by the numeral 18, and secured to the upper face of the housing by means of a clamping plate 19 and bolt 20, the unit 18 being preferably electrically operated for applying suitable heat to the material of which the crystals are made to facilitate the working of the material in the formation of the crystal. In the present structure electric current may be supplied from any suitable

source through wires 20 and 21 connected to the posts 23 and 24, respectively, mounted in an insulating block 25 secured to the clamping plate 19 by means of a screw 26. The post 23 may be connected to one end of a suitably formed heating coil, of any desired construction, arranged in the unit 18, the opposite end of the coil being connected to a terminal post 27 mounted in the insulating block 25.

Suitably mounted on the posts 24 and 27 are terminal plates 28 and 29 respectively, said plates being formed preferably of resilient material and having their free end portions spaced apart and overlying each other as illustrated in Figs. 3 and 4 of the drawings.

Slidably mounted in the housing 15 preferably adjacent the free ends of the terminal plates 28 and 29, and suitably insulated from the housing, is an electric connector 30 adapted to be moved inwardly of the housing against the action of a spring 31 in a manner to engage the adjacent faces of the terminal plates 28 and 29 as illustrated in Fig. 3 to complete an electric circuit through the heating unit.

For releasably securing the connector 30 in circuit closing position, a resilient retaining member 32 is preferably mounted on the bolt 20, and provided with a dog or latch 33 adapted to engage a shoulder 34 formed on the connector 30 to hold the connector releasably in circuit closing position as illustrated in Fig. 3. The member 32 and dog 33 are normally urged toward the connector 30 by means of a bi-metal heat responsive resilient element 35 shown in the present instance as mounted in the housing between the upper side thereof and the heating element 18, and having its free end portion operatively related to the member 32 in a manner to normally hold the dog 33 in engagement with the shoulder 34 of the connector 30 when the latter is in circuit closing position as illustrated in Fig. 3.

Pivottally mounted on trunnions 36 and 37, secured preferably to opposite sides of the housing 15, is a yoke or bail 38 having an intermediate portion 39 adapted to extend across the upper side of the housing 15 in spaced relation with respect thereto.

Mounted on the portion 39 is a sleeve 40 having external screw threads formed on its outer surface adapted to cooperate with internal threads formed in a boss 41 of clamping or pressure nut 42, the inner portion or opening in the sleeve 40 being adapted to slidably receive a hollow tube like member 43 operatively related at its upper end to the nut 42 in a manner to be moved downwardly thereby, and having secured to its lower end portion an inverted cup like member 44 adapted to receive a flexible, resilient, and preferably compressible disc like pressure member 45 of suitable material such, for ex-

- ample, as rubber, felt or the like, adapted to engage the upper side of a sheet of flexible and pliable material indicated by the numeral 46 of which the crystal is to be formed, and 5 in a manner to secure the material in desired position on the bezel of a watch case or the like, indicated in Figs. 2 and 3 by the numeral 47, when the clamping nut 42 is rotated and moved downwardly along the sleeve 40.
- 10 Screw threaded into a sleeve 43a secured to the tube 43 is a pressure or doming rod or plunger 48 adapted to be moved longitudinally through the tube 43, and having a ball 49 positioned adjacent its lower end within 15 the tube 43 and engageable with the upper face or surface of the member 45 in a manner to exert pressure thereon and flex the member 45 and material 46 when the rod 48 is rotated by means of the knurled head 50 in a 20 manner to move the rod downwardly through the tube 43, thereby forcing a portion of the material 46 into the opening formed in the bezel 47.

In forming the crystal for a watch case 25 having the bezel permanently attached thereto such as illustrated in Fig. 3 of the drawings, the operation of the device is substantially as follows:

After removing the works or operating 30 mechanism from the case, the case with the bezel attached thereto is positioned substantially centrally on the upper side of the housing 15 with the bezel of the case uppermost and a strip of material 46 of which the crystal 35 is to be formed is positioned on top of the bezel in a manner to completely cover the opening formed therein, after which the clamping nut 42 is manipulated in a manner to force the member 45 snugly against the 40 upper face of the material in a manner to clamp and hold it in desired position between the face of the bezel and the member 45. The connector 30 is then moved into engagement with the terminal plates 28 and 29 as illustrated in Fig. 3 by pressing the button 51 inwardly against the action of the spring 31, thereby completing the circuit through the heating unit 18 for heating the material 46 to the desired degree to facilitate the formation 45 of a portion thereof into a crystal.

By reason of the well known construction 50 of the bi-metal heat responsive element 35, when the desired or predetermined amount of heat has been applied, the free end of the element will be drawn upwardly in a manner to permit the resiliency of the member 32 to move the dog 33 out of engagement with the shoulder 34 thereby permitting the spring 31 to move the connector 30 out of circuit closing engagement with the terminals 28 and 29. The knurled head 50 is then manipulated to move the rod downwardly through the tube 43 in a manner to cause the ball 49 to force the flexible disc 45 and a portion of the strip 55 material 46 into the opening formed in the

bezel of the watch case a suitable distance to provide a dome or raised portion in the crystal of desired height for permitting free operation of the hands of the watch.

After the lapse of sufficient time, preferably a few seconds, in which to permit the material to set, the head 50 and clamping nut 42 may be manipulated to permit the material in the form illustrated in Fig. 12 to be removed from the device, and thereafter by firmly tracing with a suitable sharp pointed instrument, the outline indicated at 52 in Fig. 11, formed by the edges of the bezel adjacent the opening therein, the material surrounding the dome like portion 53 may be separated therefrom. If desired any rough edges of the crystal may then be smoothed by the use of a file or the like and the crystal mounted in the bezel.

As is well known by those familiar with the art to which the present invention pertains, various amounts of clearance beneath the crystal are required for the hands of the watch, and for predetermining or limiting the movement of the plunger rod 48 and flexible member 45 to obtain the desired clearance a doming gauge 54 (see Figs. 3 and 5) is pivotally mounted by means of a pivot pin 55 on the clamping nut 42, and provided with a relatively large aperture 56 adapted to receive the plunger rod 48 and, if desired of sufficient dimensions to receive a boss 57 formed on the head 50. At one side of the aperture 56, the material of the gauge 54 is cut away as indicated at 58 thereby providing a step to be engaged by the boss 57 when the gauge is adjusted to provide a crystal of medium height.

It will be observed that by the use of a gauge such as that described, domes of various height may be obtained, for example, if the gauge 54 is adjusted to a position where the boss 57 will engage the top face of the gauge and so limit the downward movement of the rod 48, a dome of relatively low height will be formed in the material 46, whereas if the gauge is positioned with the opposite side of the aperture 56 adjacent the rod 48 as shown in Fig. 5, the rod will be permitted greater downward movement until the boss 57 engages the step formed as indicated at 58, thereby permitting the material to be pressed further into the opening formed in the bezel and providing a dome of greater height, and if the gauge 54 is shifted to a position where the aperture 56 is concentric with the axis of rotation of the rod 48, the boss 57 may be moved downwardly through the aperture 56 and into engagement with the upper face of the nut 42 thereby permitting the material of which the crystal is formed to be forced still further into the opening formed in the bezel, and provide a dome of still greater height as is usually desirable in watches of relatively larger size.

For varying the degree of heat necessary to actuate the heat responsive element 35 and permit the connector 30 to be withdrawn from engagement with the terminals 28 and 29, 5 an adjusting screw 59 (see Figs. 1, 2, 3 and 6) is screw threaded into an aperture formed in a wall of the housing 15 in a manner to engage the heat responsive element 35 within the housing, and it will be observed that by 10 manipulating the screw 59, the heat responsive element 35 may be adjusted with respect to the member 32 in a manner to exert more or less pressure thereon and thereby require a greater or lesser degree of heat to 15 flex or warp the heat responsive element 35 sufficient to permit removal of the dog 33 from engagement with the shoulder 34 of the connector 30.

In Figs. 6 to 10 inclusive are shown bezel 20 adapters or spacing frames 60 intended for use in the formation of crystals for watches wherein the bezel is detachable, and in which instance it is desirable to suitably support the bezel in proper position to insure the efficient 25 operation of the crystal forming device. The spacing frames shown in Figs. 9 and 10 have apertures 61 and 62 formed therein of relatively different size to permit the material to be pressed into the opening formed in the bezel a sufficient distance to 30 provide a dome of the desired height, the openings 61 and 62 formed in the frames being determined by the size or diameter of the bezel to be fitted.

For properly centering the spacing frames 35 61 on the housing 15, a centering ring 63 is provided with outwardly and downwardly extending projections or fingers 64 adapted to engage the sides of the housing 15 in a manner to center the ring thereon, the opening 65 in the ring being of sufficient diameter to receive the frames therein as shown in Figs. 6 and 7.

It will be observed from the foregoing description that the present invention provides a device for forming crystals for watch cases and the like wherein the material may be suitably heated to a desired or predetermined degree to facilitate the formation of the crystal, and wherein the operation of the doming or shaping means may be determined and controlled to provide a crystal of the desired height. Furthermore, that the present invention enables the use of the bezel to which the particular crystal is to be applied, as a template in forming the crystal thereby insuring a proper fit of the crystal and desirable protection for the watch mechanism.

Obviously the present invention is not limited to the precise construction and arrangement shown and described, as the same may be variously modified. Moreover, all the features of the invention need not be used 60 jointly, as the same may be used to advantage

in variously different combinations and sub-combinations.

What I claim as new and desire to secure by Letters Patent is:

1. In a device of the class described, the combination of a base for supporting thereon the bezel of a watch case or the like and material to provide a crystal therefor, thermostatically controlled means mounted on said base for heating said material, means cooperable with the bezel for shaping said material to form the crystal, and a gauge for controlling the operation of such shaping means. 70

2. In a device of the class described, the combination of a base for supporting thereon the bezel of a watch case or the like and material to provide a crystal therefor, means for heating the material, a thermostat for controlling the operation of said heating means, 80 means for adjusting said thermostat, means cooperable with the bezel for shaping said material to form the crystal, and a gauge for controlling the operation of said shaping means. 85

3. In a device of the class described, the combination of a base for supporting thereon the bezel of a watch case or the like and material to provide a crystal therefor, means for clamping the material in desired position on the bezel, means for heating the material, a thermostat for controlling the operation of said heating means, means for adjusting said thermostat, means cooperable with the bezel for shaping said material to form the crystal, 95 and a gauge for controlling the operation of said shaping means. 100

4. In a device of the class described, the combination of a base for supporting thereon the bezel of a watch case or the like and material to provide a crystal therefor, adjustable means for clamping the material in desired position on the bezel, means for heating the material, a thermostat for controlling the amount of heat applied to the material, means 110 for adjusting the thermostat, means cooperable with the bezel for shaping said material to form the crystal, and a gauge for controlling the operation of said shaping means. 115

5. In a device of the class described, the combination of a base for supporting thereon the bezel of a watch case or the like and material to provide a crystal therefor, adjustable means for clamping the material in desired position on the bezel, means for heating 120 the material, a thermostat for controlling the amount of heat applied to the material, means for adjusting said thermostat, adjustable means cooperable with the bezel for shaping said material to form the crystal, 125 and an adjustable gauge for controlling the operation of said shaping means.

6. In a device of the class described, the combination of a base for supporting thereon the bezel of a watch case or the like and 130

material to provide a crystal therefor, means for clamping the material in desired position on the bezel including a flexible member adapted to engage the face of the material, and means for flexing said member in a manner to force a portion of the material into the opening formed in the bezel.

7. In a device of the class described, the combination of a base for supporting thereon the bezel of a watch case or the like and material to provide a crystal therefor, adjustable means for clamping the material in desired position on the bezel including a resilient member adapted to engage one face of the material, means for heating the material, and adjustable means for flexing said member in a manner to force a portion of the material into the opening formed in the bezel.

8. In a device of the class described, the combination of a base for supporting thereon the bezel of a watch case or the like and material to provide a crystal therefor, adjustable means for clamping the material in desired position on the bezel including a resilient compressible member adapted to engage one face of the material, means for heating the material, adjustable means for flexing said member in a manner to force a portion of the material into the opening formed in the bezel, and means for controlling the operation of said flexing means.

9. In a device of the class described, the combination of a base for supporting thereon the bezel of a watch case or the like and material to provide a crystal therefor, adjustable means for clamping the material in desired position on the bezel including a resilient member engageable with the face of the material, means for heating the material, a thermostat for controlling the operation of said heating means, adjustable means for flexing said member to force a portion of the material into the opening formed in the bezel in a manner to provide said portion with a dome-like formation having an outline of substantially the form of said opening, and a gauge for controlling the movement of said flexing means.

10. In a device of the class described, the combination of a housing having means associated therewith for supporting the bezel of a watch case or the like and material to provide a crystal therefor, a yoke pivotally mounted on said housing, adjustable clamping means mounted on said yoke including a resilient member adapted to engage the material in a manner to secure the material in desired position on the bezel, an electric heating unit mounted in said housing and having terminals associated therewith and spaced apart from each other, a movable connector adapted to engage said terminals to complete an electric circuit, a retainer for releasably securing said connector in engagement with said terminals, a heat responsive

element operatively related to said retainer for releasing said connector at a predetermined temperature, means for moving said connector out of engagement with said terminals when released, means for adjusting 70 said heat responsive element in a manner to actuate said retainer and release said connector at various temperatures of a desired degree, adjustable means mounted in said clamping means for flexing said resilient 75 member to force a portion of the material into the opening formed in the bezel in a manner to provide said portion of material with a dome-like formation having an outline of substantially the form of said opening, and a gauge for controlling the movement of said flexing means.

11. In a device of the class described, the combination of a base for supporting thereon the bezel of a watch case or the like and material to provide a crystal therefor, interchangeable bezel adaptors or positioning frames adapted to be mounted on said base, a centering ring cooperable with said base for positioning said adaptors thereon, adjustable means for clamping the material in desired position on the bezel including a flexible member adapted to engage the face of the material, and adjustable means for flexing said member in a manner to force a portion of the material into the opening formed in the bezel.

In witness whereof, I hereunto subscribe my name this 14th day of August, A. D. 1929.
